UNITED STATES PATENT OFFICE.

RICHARD HART, OF MILWAUKEE, WISCONSIN, ASSIGNOR TO ADOLPH A. RALOFF, JR.,
OF THIENSVILLE, WISCONSIN.

LEATHER-FLEXING MACHINE.

1,355,965.

Specification of Letters Patent. Patented Oct. 19, 1920.

Application filed June 10, 1918. Serial No. 239,157.

To all whom it may concern:

Be it known that I, RICHARD HART, a citizen of the United States, residing at Milwaukee, county of Milwaukee, and State 5 of Wisconsin, have invented new and useful Improvements in Leather-Flexing Machines, of which the following is a specification.

My invention relates to improvements in 10 machines for treating leather, with especial reference to machines for flexing leather.

The object of my invention is to provide means for mechanically graining leather, whereby the processes heretofore carried on 15 by hand may be efficiently performed by machinery and the work greatly expedited.

In the drawings:

Figure 1 is a fragmentary elevation of the left hand end portion of my improved 20 machine as seen from the feeding in side.

Fig. 2 is a sectional view drawn on line 2—2 of Fig. 1.

Fig. 3 is an end elevation showing the arrangement of the driving gears.

Fig. 4 is an end elevation with the driving mechanism removed.

Like parts are identified by the same reference characters throughout the several views.

30 A set of parallel, superposed rollers A and B are arranged to revolve in proximity to each other, and each of these rollers is provided with annular grooves —a— and —b— respectively. A roller C having its axis 35 midway between the axes of the rollers A and B and in the rear thereof is provided with a series of annular flanges —c— spaced apart in accordance with the distances between the grooves —a— in the rollers A and 40 the grooves —b— in the roller B, the grooves in the respective rollers A and B being so disposed that the flanges C may register with them.

The three rollers A, B, and C are revolved 45 in the same direction. A strip or piece of leather D which is to be flexed or grained is fed inwardly from the front side between the rollers A and B until its advancing margin strikes the edges of the circular flanges —c— on the roller C. The contact- 50 ing surfaces of these flanges move upwardly and carry the edge of the hide or piece of leather into contact with the periphery of the roller A whereupon this edge or margin 55 of the hide is folded over the infeeding por-

tion and carried outwardly from between the rollers A and B on the same side thereof, (herein termed the front side of the machine), as indicated by the arrows applied to the leather strip in Fig. 2.

It is desirable that the rollers A and B should be made adjustable with reference to each other in order that they may be ad- 60 justed in greater or less proximity to each other in accordance with the quality or

thickness of the leather. I have therefore provided end standards E in which the shafts —F— and —F'— of the rollers A and B are mounted, suitable bearings being

provided for that purpose. The bearings G 70 of the bearing shaft F may be fixed to the standards, whereas the bearings G' of the lower shaft F' are made vertically adjust- 75 able in suitable slots H, the walls of which

constitute guiding members for the bearings G'. These bearings at either end of the ma- 80 chine may be simultaneously raised or lowered by means of an adjustable beam or bar I mounted on a centrally disposed post J which may be actuated by means of a lever K as indicated in Fig. 4. The specific

means for adjusting these bearings is not material to my invention.

Roller C is preferably adjustably mounted 85 in a horizontal plane, whereby the folding point, or line along which the leather strip is folded, may be shifted toward the front or rear. Normally, the folding point or line

will be approximately in the vertical plane which includes the axes of the rollers A and 90 B or a little to the rear thereof, but with

leather of differing quality or stiffness, it will be found desirable to shift the roller C forwardly or rearwardly, and ordinarily 95 it will be desirable to move it rearwardly for

relatively stiff or thick leather, whereas for the lighter or more flexible grades the roller C should be adjusted forwardly, and the folding operation should take place substan- 100

tially at the points where the rollers A and B approach most closely to each other. Figs. 2 and 4 show in full lines the position of the rollers C for easily flexed or relatively light leather and in dotted lines the position of the rollers C for relatively heavy leather.

It will be observed that the shaft ends or trunnions F'' of the roller C are mounted in suitable bearings G'' in slots or guideways H' formed in the standards E.

Roller A is driven from a vertically dis- 110

- posed shaft L through the beveled gear wheels M. Sleeve N on the same shaft carries a beveled gear wheel O which drives the shaft F' of roller B through the intermeshing gear wheel O'. The sleeve N is vertically adjustable along the shaft L, being mounted between the sliding collars P and P' carried by a bracket Q which is connected with the sliding bearing block G' in which shaft 5 F' is journaled, the arrangement being such that shaft F' may be raised or lowered without disengaging the motion-transmitting connections between it and the driving shaft L.
- 10 Motion is transmitted from the upper shaft F to the roller C through a train of gears R, R', and R'', the gear wheel R' constituting a floating gear wheel supported by links S and S' from the shafts F and F'' 15 on which the other gear wheels R and R'' are mounted. Therefore when the shaft F'' of the roller C is moved horizontally, the intermediate floating gear wheel R' will move inwardly or outwardly and maintain 20 its driving relation in the train of gears R, R', and R'' in any position of adjustment 25 of the roller C.
- The operation of the machine is as follows: Leather is passed by the bottom roller 30 B in between this roller and the top roller A. When the edge of the leather reaches the roller C such edge will be carried upwardly against the roller A. The roller A will carry this edge outwardly above the 35 lower incoming leather. This operation then continues, the leather being fed inwardly by the roller B, outwardly by the roller A, and upwardly by the roller C. The bight or fold of the moving leather 40 is retained between the rollers A and B without the use of an additional member or guide within the fold. This is made possible by positioning the fold line far enough rearwardly between the rolls A and B, by 45 the adjustment of the roll C to suit the stiffness of the leather, that the folded portion be caught in the form of a loop between the rolls A and B. In the case of some leathers, particularly the soft thin grades, the roller 50 C may be adjusted inwardly to its extreme position as shown in Figs. 2 and 4, but for thicker or stiffer leather the roller C is moved back toward, or to, the dotted line position to allow the leather to expand along 55 the folding line in the form of a small cylindrical roll beyond the most constricted portion at the plane common to the axes of the rolls A and B.
- Nothing herein contained is intended to 60 limit the scope of my invention to the specific structure and arrangement described, the mechanism illustrated in the drawings being intended merely to indicate a convenient form of mechanism in which 65 my invention may be embodied.

I claim—

1. A leather flexing machine adapted for graining leather, comprising the combination of three parallel rollers, two of which are separated to permit the folding of sheets 70 of leather in the space between them, each of said two rollers being provided with opposing annular grooves in their peripheries, and the third roller having its axis located on one side of said two rollers substantially 75 opposite the space between them, said third roller having flanges loosely entered in said annular grooves, and crossing said space near a plane common to the axes of the grooved rollers, the space between said 80 grooved rollers on the opposite side of said plane being unobstructed to allow a leather sheet to fold or double upon itself within said space, and means for revolving all of said rollers in the same direction, whereby 85 leather sheets may be fed between the grooved rollers on the inwardly moving surface of one of them, and carried outwardly on the same side of the set in contact with the outwardly moving surface of the other 90 grooved roller without friction and with a free bending movement.

2. A leather flexing machine adapted for graining leather, comprising the combination of a set of parallel rollers having peripheries annular grooves opposing each other in the respective rollers, a third roller 95 having flanges loosely fitting within the grooves in the other two rollers, means for actuating all of said rollers in the same direction, and means for relatively adjusting the grooved rollers into greater or less proximity to each other, at the will of the operator, the space between the grooved rollers on the side opposite that occupied 100 by the flanged roller being wholly open and unobstructed to allow a free folding of leather sheets when fed between said 105 grooved rollers into contact with the flanges of the third roller.

3. A leather flexing machine adapted for graining leather, comprising the combination of a set of parallel rollers having peripheries annular grooves opposing each other in the respective rollers, a third roller 115 having flanges loosely fitting within the grooves in the other two rollers, means for actuating all of said rollers in the same direction, and means for adjusting the flanged roller, with the peripheries of the flanges 120 in greater or less proximity to a plane which includes the axes of the grooved rollers, the space between the grooved rollers on the side opposite that occupied by the flanged roller being wholly open and unobstructed 125 to allow a free folding of leather sheets when fed between said grooved rollers into contact with the flanges of the third roller.

4. A leather flexing machine adapted for graining leather, comprising the combina- 130

tion of a set of parallel rollers having peripheral annular grooves opposing each other in the respective rollers, a third roller having flanges loosely fitting within the 5 grooves in the other two rollers, means for actuating all of said rollers in the same direction, and means for relatively adjusting the grooved rollers into greater or less proximity to each other and also adjusting 10 the flanged roller with the flanges entering the grooves of the other rollers to a greater or less distance from a line joining the centers of the other two rollers, the space between the grooved rollers on the side opposite that occupied by the flanged roller being wholly open and unobstructed to allow 15 a free folding of leather sheets when fed between said grooved rollers into contact with the flanges of the third roller.

20 5. A leather flexing machine adapted for graining leather, comprising the combination of a set of parallel rollers having peripheral annular grooves opposing each other in the respective rollers, a third roller 25 having flanges loosely fitting within the grooves in the other two rollers, means for adjusting said third roller, means for actuating all of said rollers in the same direction, a common driving shaft, and means for 30 maintaining driving connection between said shaft and each of the rollers in the various positions of roller adjustment, the space between the grooved rollers on the side opposite that occupied by the flanged 35 roller being wholly open and unobstructed to allow a free folding of leather sheets when fed between said grooved rollers into contact with the flanges of the third roller.

6. A leather flexing machine adapted for 40 graining leather, by progressively folding a piece of leather upon itself, comprising the combination of a set of parallel rollers having generally cylindrical peripheral surfaces broken at intervals by annular grooves opposing 45 each other in the respective rollers, a third roller having flanges loosely fitting within the annular grooves of the other two rollers, with the peripheries of said flanges

in proximity to a plane which includes the axes of said other two rollers at a point midway between said rollers, means for adjusting said third roller, and means for actuating all of said rollers in the same direction, 50 the space between the grooved rollers on the side opposite that occupied by the flanged roller being wholly open and unobstructed to allow a free folding of leather sheets when fed between said grooved rollers into contact with the flanges of the third 55 roller.

7. A leather flexing machine adapted for graining leather, comprising the combination of three parallel rollers, two of which are separated to permit the folding of sheets of leather in the space between them, each 60 of said two rollers being provided with opposing annular grooves in their peripheries, and the third roller having its axis located on one side of said two rollers substantially 65 opposite the space between them, said third roller having flanges loosely entered in said annular grooves, and crossing said space near a plane common to the axes of the grooved rollers, the space between said 70 grooved rollers on the opposite side of said plane being unobstructed to allow a leather sheet to fold or double upon itself within said space, means for revolving all of said rollers in the same direction, whereby 75 leather sheets may be fed between the grooved rollers on the inwardly moving surface of one of them, and carried outwardly on the same side of the set in contact with the outwardly moving surface of the other 80 grooved roller without friction and with a 85 free bending movement, and means for adjusting said third roller toward and away from a plane common to the axes of the grooved rollers.

In testimony whereof I affix my signature 90 in the presence of two witnesses.

RICHARD HART.
